US0D1058670S

(12) **United States Design Patent** (10) **Patent No.:** **US D1,058,670 S**
(45) **Date of Patent:** **** Jan. 21, 2025**

(54) **PEN HOLDER**

(71) Applicant: **Shenzhen Ninth Season Technology Co., Ltd.**, Shenzhen (CN)

(72) Inventor: **Zhengqiang Zhang**, Shenzhen (CN)

(**) Term: **15 Years**

(21) Appl. No.: **29/780,551**

(22) Filed: **Apr. 26, 2021**

(51) LOC (15) Cl. **19-06**

(52) U.S. Cl.

USPC **D19/203**
